UNITED STATES PATENT OFFICE

ALFRED F. WIEDENHOEFT, OF CHICAGO, ILLINOIS

LAMP

Application filed January 5, 1929. Serial No. 330,476.

My invention relates to lamps.

In particular my invention is concerned with that type of lamp which has a shade overlying the electric bulb and which shade has a depending skirt so as to cause the light to be directed downwardly and not directly into the eye of the observer.

One of the objects of my invention is to shiftably mount the shade upon the lamp so that the shade may be tilted upwardly at one side of the lamp to permit the light rays to be reflected laterally and in a substantially horizontal plane, and in such a manner that when the shade is returned to its original position it will not be permitted to swing in the opposite direction but will return to a true vertical position symmetrically overlying the lamp bulb.

A further object of my invention resides in means for holding the shade in any adjusted position.

Still another object of my invention resides in a very simple and economical construction which is at the same time highly efficient and pleasing in appearance.

In another aspect my invention resides in providing a lamp with a supporting upright which upright is adapted to carry an ornamental panel useful for various purposes, such for instance as carrying the name of the hotel in which the lamp is installed or carrying a fraternity crest where the lamp is used by students in colleges or by carrying a club insignia.

Another object of my invention resides in arranging this panel preferably as a transparent or translucent ornamental indicia carrying member adapted to be insetted in the upright of the lamp and arranged so as not to interfere with the electrical cables which are mounted in this upright.

An ancillary object of this feature of my invention resides in the arrangement of means for replacing these panels as for repair or interchangeability and particularly in the means for hiding or masking the replacing means so that to all intents and purposes the panel is permanently mounted within the lamp and so that to all intents and purposes the panel containing upright is not provided

with any electrical conduits or cables in its interior.

These and other objects of my invention will be more apparent from a perusal of the following specification when taken in connection with the accompanying drawings, wherein:

Figure 1 is a front view of one type of my improved lamp showing the shade construction in detail;

Figure 2 is a view taken at right angles thereto;

Figure 3 is a top view of the inner portion of the shade support;

Figure 4 is an exploded view of the panel and its keeper removed from the upright;

Figure 5 is a sectional view showing the panel and keeper in assembled position;

Figure 6 is a front view in section showing the panel and electrical conduits in position;

Figure 7 is a sectional view at right angles thereto;

Figure 8 is a modified form showing the manner in which the panel may be inserted from the narrow side of the upright;

Figure 9 is a view at right angles thereto;

Figure 10 is a front view of Figure 8; and

Figure 11 is a cross sectional view of Figures 8, 9 and 10.

Referring now to the lamp in detail, it comprises a base 2 of any suitable construction which rigidly carries an upright 4. This upright may be of any desired ornamental configuration but in the present instance, it comprises a substantially oval shaped portion 6 having an opening 8 so as to provide two looping arms or branches 6 and 10, which come together above the opening 8 at the point 12 and continue upwardly as at 14 to provide a socket portion 16 for the lamp proper. In addition the base 18 of the socket portion is formed as a sleeve and carries integral rod-like portions 20, there being preferably 3 in number, which at their upper ends rigidly support a metal cap 22 having an upper dome shaped portion 24 of substantially truly spherical contour. Substantially half-way down on this spherical dome, it is provided with a peripheral bead or shoulder 26 providing a raised portion. If desired, this bead 26

is formed as a sleeve and carries integral rod-like portions 20, there being preferably 3 in number, which at their upper ends rigidly support a metal cap 22 having an upper dome shaped portion 24 of substantially truly spherical contour. Substantially half-way down on this spherical dome, it is provided with a peripheral bead or shoulder 26 providing a raised portion. If desired, this bead 26

may be replaced by a peripheral ring of punched out portions. In addition, the dome portion 24 is provided with a radially extending slot 28 which extends from the central axis of the dome downwardly to a point 30. The shade 32 has an upper dome shaped portion 34 of circular contour to correspond to the contour of the dome 24 and the shade in addition has a skirt 36 which depends substantially to the socket 18 so as to direct the light rays downwardly. The usual electric lamp 38 is detachably mounted within the usual standard socket 16 and the light is turned off and on by the usual switch connection 40.

In order to hold the shade in any adjusted position while permitting it to tilt upwardly so as to cast the light rays in a substantially horizontal direction, if desired, I provide a pin 42, the lower end of which has a head 44 inserted from the under side of the dome 24 and passing through the slot 28 thereof. This pin passes through a circular hole in the dome 34 of the shade and thence into an ornamental fitting 44' having an aperture of two dimensions, the first to receive a coil spring 46 and the second to receive a threaded nut 48. This nut engages threads on the pin 42 so as to press the head of the bolt 44 upwardly whereby to cause the peripheral rib 26 in the dome frictionally to engage the under side of the dome shaped portion 34 of the lamp shade. Thus, when the shade is swung upwardly to the left, as shown in Figure 2, the ornamental fitting 44' will be shifted to the right as shown in dotted lines and the shade will be tilted upwardly as shown in dotted lines in Figure 2. By reason of the raised portion such as the peripheral ring 26, the friction and wear is reduced to a minimum while at the same time the shade is frictionally held in any adjusted position.

The foregoing construction is very simple and one of its particular features resides in the fact that when it is desired to return the lamp shade to normal vertically depending position, shown in Figure 1, it is but necessary to press upon the raised portion of the shade to force it downwardly and by means of my improved construction the shade will stop at its symmetrically depending position and will not overswing to another raised position. This is of great convenience in hotels, clubs, fraternity houses and the like, where an attendant is desirous of returning lamp shades to their vertical position so that the various shades will not be at different angles, which presents an unsightly appearance.

In another aspect of my invention, it is highly desirable to provide lamps with an ornamental panel which may be used to indicate the ownership of the lamp or whereby the panels may be provided with appropriate indicia as for instance a club, society, fraternity, or name of hotel or appropriate

emblem and I have provided a very unique, economical and pleasing construction which permits such indicative panels to be set directly into the upright of the lamp and in such a manner as to not only permit its 70 ornamentation but to also effectively hide or mask the manner in which the panels are inserted. In addition, I have accomplished this so as not to interfere with the electric cables or wires passing upwardly through this upright to the lamp bulb proper. In the particular construction illustrated, I have shown my panel as being a piece of transparent glass carrying an appropriate symbol. This piece of glass 50 is in general the 75 shape of the opening 8 in the upright. In the particular construction illustrated, the arms or branches 6 and 10 of the upright are suitably constructed so as to provide a gutter 52 in each branch and this is accomplished by forming the metal or material of the upright substantially as shown in Figures 4 and 5 above the opening 8 in the upright. I also provide a keeper 54 which is likewise provided with a central opening 56 and two 80 branch arms 58 of corresponding shape to fit snugly within the open side of the upright substantially as shown in Figure 4. This keeper is provided with two lugs or ears 60 and 62 which are perforated as at 85 64 to receive screws 66 for holding the keeper in position with the panel 50 assembled therein. It will be noted that by reason of my construction I am enabled to provide a keeper which balances the ornamentation on the other side of the upright and will substantially hide the lines of the keeper so that without a very careful inspection, the presence of the keeper or the presence of the opening in the upright cannot be detected.

In addition, it will be noticed that by my construction I am enabled to pass the electric wires or conduits 66', which pass upwardly through the base 4, in a manner such that a single wire or cable will lie in a separate gutter 52 on each side of the opening 8 and so that these cables above the opening will then come together and pass upwardly through the hollow portion 14. It will also be seen from an inspection of Figure 5 that the panel 50 will overlie these cables 66' as they rest in the gutters so as to hold them in position and that the keeper 54 will hold the panel in position.

In the construction shown in Figures 8, 9, 10 and 11, instead of inserting the panel from the front or flat face of the upright, I desire to insert the same through a relatively narrow or small slot in the side of one of the branch members. To this end, the plug or keeper 68 will fill up or close a slot 70 formed in the side 72 of the hollow upright 74 and is retained in such position by means of a set screw or screw 76. In this connection, the branch wall 72 has a slot passing entirely 100 105 110 115 120 125 130

therethrough while the opposite branch wall 80 of the upright has a slot passing only part way therethrough so as to form a gutter for the two cables or electric wires, the panel 5 82 holding them in position.

From the foregoing it will be seen that this panel construction provides a very effective way in which lamps may not only be ornamented but may be provided with a very 10 useful adjunctive device to determine the ownership or association of the lamp.

In addition the construction is such that these panels may be very quickly and easily interchanged while at the same time the appearance of the lamp is not only enhanced by the panel but due to the manner of mounting the same it is not apparent, without very close inspection, how the panel is detachably mounted within the lamp. Moreover, due 20 to the presence of the panel opening in the standard for the lamp, it is not apparent how the electric cables pass upwardly through the upright to the electric lamp thereby producing a very pleasing and somewhat mystifying effect.

Having thus described my invention, what I claim as new and desire to secure by Letters Patent is:

1. In a lamp of the character described, the combination of a hollow upright adapted to receive electric wires, said upright having a yoke shaped portion forming a central aperture and two curved arms joined above and below the hollow portion, at least one of said 35 arms being provided with a gutter for the reception of an electric connection passing through the hollow support, said yoke shaped portion having a cutout, an indicia bearing plate for the opening in said yoke shaped portion, a keeper or plug for the indicia bearing plate, and means for holding said keeper in position.

2. In a lamp of the character described, the combination of a hollow upright adapted to receive electric wires, said upright having a yoke shaped portion forming a central aperture and two curved arms joined above and below the hollow portion, at least one of said arms being provided with a gutter for the 45 reception of an electric connection passing through the hollow support, said yoke shaped portion having a cutout, an indicia bearing plate for the opening in said yoke shaped portion, a keeper or plug for holding the indicia bearing plate in the yoke, and means for holding said keeper in position, said indicia bearing plate engaging the electric wires to hold the same in position in the gutter.

3. A lamp having a hollow upright for the reception of electric wires, said upright having a yoke shaped portion providing an aperture and opposed branch arms joining above and below the aperture, the branch arms of 65 the aperture being provided with an internal

gutter for the reception of the electric wires, the yoke shaped portion having a cut-out for the reception of indicia bearing plate, said plate engaging the electric wires and gutters to hold the same in position, and a keeper 70 for the plate, and means for holding the keeper in position.

4. A lamp of the character described having a hollow upright, electric wires passing through said hollow upright to the electric 75 lamp, said upright having an opening directly in the bottom portion thereof and a transparent plate mounted in said opening, and a keeper overlying the transparent plate, said keeper forming a portion of the upright when in position, and means for holding the keeper in position.

5. A lamp having an upright formed with an opening therein and providing two branch arms joined to the upright above and below the opening and forming said opening, one of said arms having a slot in the side thereof communicating with the opening and the other arm having a registering groove, a 80 transparent plate adapted to be inserted through the slot to close the opening and to have its edge rest in the groove in the other arm, and a plug or keeper adapted to close the slot in the first mentioned arm, and means 85 for holding the plug in position, and means for passing electric wires up through the upright and through a groove in one of the arms and up through the upper portion of the upright to the lamp.

In witness whereof, I have hereunto subscribed my name.

ALFRED F. WIEDENHOEFT.
